UNITED STATES PATENT OFFICE.

PATRICK JOSEPH ELLIOTT AND EDWARD L. BONAMY, OF NEWCASTLE, WASHINGTON.

MINE-CAR COUPLER.

Application filed June 17, 1922. Serial No. 569,172.

To all whom it may concern:

Be it known that we, PATRICK J. ELLIOTT and EDWARD L. BONAMY, a subject of Great Britain and a citizen of France, respectively, 5 residing at Newcastle, county of King, and State of Washington, have invented a new and useful Mine-Car Coupler; and we do hereby declare that the following is a full, clear, and exact specification, such as will enable others skilled in the art to which it 10 pertains to make and use the same.

The invention is a device which will automatically release a car from a cable pulling it as the cable is raised to a vertical position 15 over it.

The object of the invention is to provide a device with lugs on its interior surface which will slip into slots in the tongue of a car and remain in place while the car 20 is being pulled but which will slip out of place and release the car as the cable that is pulling it is raised to a vertical position.

Another object of the invention is to provide a frame with a roller at the end above 25 a track so that as a cable pulling a car passes over the roller when the car is released it will drop off the side of the frame automatically to a position in front of another car so that it may be readily attached to the 30 car.

With these ends in view the invention embodies an inverted U shaped bracket with slanting lugs on the inside of its vertical sides and trunnions on the outside. The 35 trunnions have straps pivoted on them whose opposite ends are bent inward and pivoted on a pin on which is also a bar which has a link in its outer end to which the end of a cable is attached and whose inner end 40 projects backward under the bracket.

Other features and advantages of the invention will appear in the following description taken in connection with the drawings, wherein,

Figure 1 is a side elevation.
Figure 2 is a bottom view.

Figure 3 is a general view showing the frame which causes the coupler to release and drop down to the next set of cars.

In the drawings we have shown our device as it would be constructed wherein, 50 numeral 1 indicates the inverted U shaped bracket which has lugs 2 on the inner side of its vertical members and trunnions 3 on the outside of them. The lugs 2 fit in slots 4 of a car tongue 5 and both the lugs and

slots are made in a slanting position as shown by the dotted lines in Figure 1. The straps 6 are pivotally mounted on the trunnions 3 and their opposite ends which are bent inward as shown in Figure 2 and pivotally mounted on the bolt 7 in which is also the bar 8, in the outer end of which is a link 9 by which the coupler is attached to the end of a cable. At the inner end of the bar 8 65 is a point 10 which is formed by cutting away the upper part of the bar as shown in Figure 1.

In Figure 3 we have shown a cable 11 pulling a full car 12 out of a mine and as 70 the car arrives at the dotted position indicated by the numeral 13 the cable 11 which runs over a roller 14 will be in practically a vertical position so that the outer end of the coupler will rise to the dotted position shown 75 in Figure 1 in which position the lugs 2 will slide upward out of the slots 4 and thereby release the cable from the end of the car. The end of the cable will then drop on top of the frame 15 and the inclined bar 16 will 80 cause the cable to slide off the end of the frame. A row of empty cars 17 standing on a siding beside the frame may then be fastened to the end of the cable and run down into the mine. From the illustration it may 85 be observed that there may be two cables and the frame may have two sides with a partition 18 in the middle and another siding for empty cars may be placed on the other side of the frame. In which case the 90 cable 11 will handle the cars on the far side of the frame and the cable 19 will handle the cars on the near side of the frame.

It will be understood that changes may be made in the construction without departing 95 from the spirit of the invention. One of which changes may be in the use of two or more lugs on the sides of the bracket 1 instead of one as shown. Another may be in the changing of the slope of the lugs. And 100 still another may be in the design of the bar 8 or in the method of attaching it to the cable.

The construction will readily be understood from the foregoing description. To 105 use the device a slanting slot should be placed in each side of a car tongue and the U shaped bracket placed over it with the lugs going into the slot. It will be seen that as the coupler is pulled forward 110 the beveled edges of the lugs will cause the bracket to pull downward against the top

of the tongue so that it will be impossible for it to slip off until the outer end of the coupler has been raised as hereinbefore described. It will be seen that in order to 5 uncouple the car it will only be necessary to push upward on the under side of the bracket.

Having thus fully described the invention what we claim as new and desire to 10 secure by Letters Patent, is:—

1. A device of the type described embodying an inverted U shaped bracket having sloping lugs on the inner sides of its vertical members and trunnions on the outside 15 of them; straps pivotally mounted on the trunnions; a pin through the outer ends of the straps; a bar pivotally mounted on the pin between the straps; means for fastening the outer end of the bar to a cable; 20 a finger on the inner end of the bar formed by cutting away a portion of the upper side; and the placing of sloping slots in the sides of car tongues.

2. A device of the type described embodying an inverted U shaped bracket; lugs on the inner sides of the vertical members of the bracket; pins projecting from the outer side of the vertical members of the bracket; links pivotally mounted on the pins 30 whose opposite ends are bent together and pivotally mounted on another pin; a bar pivotally mounted on this pin between the links; a hole in the outer end of the bar for attaching it to the end of a cable; a projection on the inner end of the bar; and the cutting of slots in the sides of a car tongue. 35

3. A mine car coupler of the type de-

scribed embodying an inverted U shaped bracket having lugs on the inner sides of its vertical members and pins projecting from the outside of them; bars pivotally mounted on these pins for connecting the bracket to a cable; and slots in the sides of a car tongue into which the lugs may be placed. 45

4. A device of the type described embodying an inverted U shaped bracket having sloping lugs on the inner sides of its vertical members and pins projecting from the outside of them; bars pivotally mounted on these pins for connecting the bracket to a cable; and sloping slots in the sides of car tongues into which the lugs on the inside of the bracket may be placed. 50

5. A device of the type described embodying an inverted U shaped bracket with lugs on the inside of its vertical members to fit in slots in the sides of car tongues; bars pivotally mounted on pins on the outside of the bracket; a pin connecting the outer 60 ends of the bars together and to a plate between them; a projection on the inner end of the plate to catch under a car tongue; a link in the outer end of the plate to connect it to the end of the cable; a frame 65 adjacent to the opposite end of the cable with a roller on its end directly above the track; and a sloping member on the frame to guide the end of the cable downward as it disconnects from the car tongue and rides 70 on top of the frame.

PATRICK JOSEPH ELLIOTT.
EDWARD L. BONAMY.
